UNITED STATES PATENT OFFICE.

FAY H. MARTIN, OF BOSTON, MASSACHUSETTS, ASSIGNOR TO TEXTILE MACHINERY COMPANY, OF BOSTON, MASSACHUSETTS, A CORPORATION OF MAINE.

FLIER FOR ROVING-MACHINES, &c.

No. 892,863.

Specification of Letters Patent.

Patented July 7, 1908.

Application filed July 15, 1907. Serial No. 383,836.

To all whom it may concern:

Be it known that I, FAY H. MARTIN, a citizen of the United States, residing at Boston, in the county of Suffolk, State of Massachusetts, have invented a certain new and useful Improvement in Fliers for Roving-Machines, &c., of which the following is a specification, reference being had therein to the accompanying drawings.

10 The invention has relation to fliers of roving frames and the like machines, and is designed as an improvement upon the invention which is described and claimed in United States Letters Patent No. 760,227, 15 granted to me May 17, 1904.

In a flier of the class to which the present invention and that of the Letters Patent aforesaid relate, the presser-finger extends in the direction of the length of the spindle 20 and is pivotally mounted so as to swing in a plane which is radial to the spindle. However, instead of being pivoted upon the presser-carrying arm so that the center of the pivot constitutes the axis or center of 25 the arc which is described by the presser-shoe in its movements, the said presser-finger is mounted upon the said arm in such a manner that, as the load of roving which is being wound upon the bobbin increases in 30 diameter and presses the shoe of the presser-finger outward from the spindle, the presser-finger, in addition to swinging outward in a radial direction, is caused to move bodily in the direction of its length. The result of 35 causing this bodily movement of the presser in the direction of its length to constitute a component of the movement of the presser in the operation of the flier, is to cause the shoe of the presser to travel outward and in- 40 ward in a substantially horizontal direction, and to stand at, or substantially at, the same height at the exterior of a wound mass of roving as when it occupies its innermost position in contact with the barrel of the bobbin. Thereby any noticeable irregularity 45 in the positioning of the ends of the successive layers of roving which are wound upon the bobbin is obviated.

In my Letters Patent aforesaid the presser- 50 finger is formed in the body-portion thereof with slightly curved arc-shaped slots that are described about a center which is at the side toward the spindle and bobbin. These slots are occupied by small tubular blocks or

bushings, counterbored at their inner ends, 55 and having such ends fitted upon the exteriors of studs or nipples that project from and are integral with the presser-carrying arm of the flier. The said studs or nipples are internally threaded to receive the screw-threaded inner end - portions of securing-screws which pass through the said blocks or bushings and also through a cap-plate at the outer ends of the blocks or bushings, the 60 said screws holding the cap-plate and blocks 65 or bushings to the said carrying-arm. The presser-finger is confined between the cap-plate and the adjacent surface of the carrying-arm of the flier, and in its movements slides up and down upon the said blocks or 70 bushings. The hollow studs or nipples were designed to constitute supports for the blocks or bushings, by which to hold the latter in position, and in addition were designed to afford proper support for the inner 75 ends of the securing screws and enable a sufficient length of screw-thread to be provided for engagement with the said ends of the screws. The wall of the presser-carrying 80 arm, it being hollow or tubular for the passage of the roving therethrough on its way from the neck of the flier to the stem and eyes of the presser-finger, is too thin to permit of being properly screw-threaded and to 85 afford proper seats for the screws.

In the Letters Patent aforesaid the presser-carrying arm is shown and described as having the threaded holes for the reception of the securing screws aforesaid continued through the entire thickness of the wall of 90 the said arm and intersecting the roving-passage within the arm. The purpose was to afford a longer seat for the inner end-portions of the securing screws. In practice, however, it was found that, in the movement 95 of a roving through the roving-passage, fibers became caught and detached from the roving and held by the edges of the holes or by the inner ends of the screws, when these last extended entirely to the guide-passage. This 100 drawback led to making shorter holes extending only as far as the inner ends of the studs or nipples. This change in construction, however, resulted in another disadvantage, namely, inasmuch as any transverse 105 strain acting through the securing screws was then withstood only by the shells or walls of the hollow studs or bushings, and in-

asmuch as these of necessity were thin and weak, while the bushings and the headed ends of the screws projected to a considerable extent beyond the studs or nipples, 5 breakage of the studs or nipples occurred, incapacitating the flier.

The first feature of my invention consists, therefore, in an improved construction of flier-arm and bushings by means of which the 10 blocks or bushings and their securing screws are more effectively applied and supported in place, and whereby the tendency to breakage, and other disadvantages, of the patented construction aforesaid are obviated.

15 It happens sometimes in the working of a roving frame or other like machine, from one cause or another, that an arm of one flier will touch or strike an arm of an adjoining flier. I have observed this tendency more particularly in the case of frames which have been in use for some time and in which the spindle-bearings have gotten more or less out of true. The second feature of my invention consists in a shield or guard for protecting the presser 25 5 of a flier from being struck and broken, bent or otherwise injured by an arm of an adjoining flier.

The invention is illustrated in the accompanying drawings, in which latter,—
30 Figure 1 shows in elevation a spindle, bobbin, and flier, having my invention applied in connection with the said flier. Fig. 2 is a view looking from the left-hand side in Fig. 1. Fig. 3 is an elevation of the presser-car-
35 ry arm, shown separately, with the presser removed. Fig. 4 is a detail view in section on line 4, 4, of Fig. 1, on an enlarged scale. Fig. 5 is a detail view on line 5, 5, of Fig. 3, also on an enlarged scale. Fig. 6 is a 40 detail view showing the weight-arm 41 of the presser-finger in section in a horizontal plane.

Having reference to the drawings,—1, Figs. 1 and 2, designates the spindle of a roving-frame, the upper portion thereof being 45 indicated by dotted lines in Fig. 1. At 1^a, Figs. 1 and 2, is a portion of the spindle-bear-
ing.

2 is a bobbin surrounding the said spindle. A load of roving upon the said bobbin is indicated by dotted lines in Fig. 1.

3 is a flier which is applied to the upper end of the spindle. The boss or nose of the flier is designated 31 in Figs. 1 and 2. The balancing arm of the flier is designated 32, and the arm to which the presser-finger is connected is designated 33. The guide-passage 34 for roving extending lengthwise within the said arm 33 is indicated by dotted lines in Fig. 1, and is represented in cross-section in 55 Figs. 4 and 5.

4 is the presser-finger, 41 being its weight-arm, 42 the presser-shoe, and 43, 43, being the eyes of the said presser-shoe through which the roving is led on its way to the bob- 60 bin.

At 44, 44, are the two curved or arc-shaped slots which are formed through the body-portion of the presser-finger, as in the Letters Patent aforesaid.

At 5, Fig. 4, is shown one of the blocks or bushings which are mounted upon the arm 33 and received within the slots 44, 44. At 7, 7, are the screws by means of which the said blocks or bushings and the presser-finger are confined in place. 75

At 6, 6, are washers upon the stems of the screws 7, 7, the said washers intervening between the heads of the said screws and the outer ends of the blocks or bushings 5 and outer side of the body of the presser-finger 80 The washers 6, 6, take in the present instance the place of the cap-plate of the Letters Patent aforesaid.

In carrying my present invention into effect, I make the flier-arm with one or more 85 enlargements *a*, *a*, and in the latter, in positions which are offset with relation to the roving-passage 34, I tap the screw-threaded holes *b*, *b*, (see, more particularly, the sectional view, Fig. 4) to receive the screw-threaded 90 portions of the screws 7, 7. This location of the said holes permits me to form the latter in material of ample thickness, greatly exceeding the thickness of the wall of the roving-passage. The said enlargements are 95 shown projecting in the form of substantially cylindrical bosses. I thereby am enabled to provide seats which receive sufficient lengths of the stems of the screws to properly hold and support the latter, and am enabled 100 also to form sufficient length of thread to hold the screws securely. The thickness at the enlargements may vary as found desirable in practice. The screw-holes *b*, *b*, are entirely outside the roving-passage, as will 105 be clear from Figs. 4 and 5, and consequently the wall of the latter is left smooth and unbroken throughout the length of the passage. The threaded hole *b* may extend completely 110 through the thickness of the material in which it is formed, as in Figs. 4 and 5, although in some instances the said hole may be closed at one end thereof. Studs or nipples such as those of the Letters Patent aforesaid may be formed upon the enlargement 115 120 or enlargements, and the blocks or bushings may be fitted thereto as in the patent, or I may employ the improved construction shown best in Fig. 4 of the accompanying drawings, in which latter the enlargement is shown counterbored around the upper end of the hole *b*, and the block or bushing 5 is shown as having its lower end received within the counterbore. Thereby the block or bushing is given lateral support by the material 125 of the arm 33, and the stem of the screw 7 is relieved from the action of lateral strain tending to bend the same. Preferably, although not necessarily in all cases, the inner end of the block or bushing is reduced in diameter, 130

the counterbore being of corresponding size to fit the same, and the said reduced portion is surrounded by a small bearing-plate 8, which rests against the outer face of the enlargement, and with which the shoulder of the block or bushing 5, and the inner face of the body-portion of the presser-finger, make contact. The two bearing-plates 8, 8, (which might be replaced by a single plate or strip) take the wear that is incident to the movement of the presser-finger.

The portions of a flier which, in the rotation of the latter, are most likely to strike against portions of an adjoining flier are those which extend farthest from the axis of rotation of the flier and its spindle. In the present instance the arms 32 and 33 incline downwardly and outwardly, so that generally speaking the lower ends of such arms, and the body-portion of the presser-finger in connection with arm 33, are the portions which are most likely to be struck. In beginning to wind upon an empty bobbin the presser-finger will occupy a position in which the presser-shoe 42 is close to the barrel of the bobbin and the weight-arm 41 extends outward somewhat. Under these conditions the weight-arm 41 of one flier may accidentally make contact with the weight-arm of one of the fliers next adjoining. However, in virtue of the fact that the weight-arms are lenticular in cross-section this contact will occasion no injury because the rounded outer surfaces of two weight-arms 41 striking together will merely glance against each other without breaking or bending anything. A blow delivered upon the counterbalancing arm 32 is not likely to occasion injury, but a blow against the body-portion of the presser-finger might damage the latter or the devices by which it is supported and guided upon the arm 33. For the protection of the said body-portion I provide the said arm 33 with a wing 9, shown best in Fig. 3, which precedes the presser-finger in the turning movement of the flier, and projects alongside and beyond the body-portion of the presser-finger so as to receive any blows which might otherwise reach the said body-portion, and thereby ward them from the latter.

Heretofore, in the case of fliers of the class to which the invention relates, the flier-body with its arms integral therewith has been produced as a casting, and the body-portion of the presser-finger has been fitted against a surface or surfaces of the presser-carrying arm, such surface having been prepared and smoothed off by machining the same. The condition of the surface or surfaces is likely to vary in the case of different fliers. For instance, when the tool that is employed for smoothing off the said surface or surfaces becomes dull it leaves the latter more or less rough. So also, the size of the portion or portions of the flier-arm on which the surface or surfaces aforesaid is

formed often varies more or less in consequence of differences in effecting the molding and casting, and as a result the diameter or length of the surface or surfaces may vary in different cases, producing thereby variations in amount of friction, etc., and in the results. The employment of prepared bearing-plates 8, 8, enables me to secure uniformity in the character of the surface or surfaces against which the body-portion of the presser-finger is held and upon which it slides, and uniformity in the working conditions and results. It also enables me to reduce the cost of preparing the said surface or surfaces, since they do not require to be finished off so perfectly as heretofore.

I claim as my invention:—

1. In a flier, in combination, the flier-arm having the longitudinal passage, enlarged laterally with relation to the said passage, and having the screw-threaded holes tapped therein in positions that are offset with relation to the passage, the swinging and longitudinally movable slotted presser-finger, and the holding screws for the said presser-finger, occupying the said offset screw-threaded holes.

2. In a flier, in combination, the flier-arm having the longitudinal passage, enlarged laterally with relation to such passage, having the screw-threaded holes tapped therein in positions that are offset with relation to the passage, and counterbored around the said holes, the blocks or bushings having their inner ends occupying the counterbores, the swinging and longitudinally movable slotted presser-finger, and the holding screws for the said presser-finger, passing through the said blocks or bushings and occupying the said offset screw-holes.

3. In a flier, in combination, the flier-arm having the longitudinal passage, enlarged laterally with relation to such passage, having the screw-threaded holes tapped therein in positions that are offset with relation to the passage, and counterbored around the said holes, the shouldered blocks or bushings having the reduced inner ends occupying the counterbores, the swinging and longitudinally movable slotted presser-finger, and the holding screws for the said presser-finger, passing through the said blocks or bushings and occupying the said offset screw-holes.

4. In a flier, in combination, the presser-finger, mounted upon an arm of the said flier and movable thereon longitudinally and also in a radial plane, and the said flier-arm provided with a shield operating to ward off blows from adjacent fliers from the said presser-finger.

5. In a flier, in combination, the presser-finger, mounted upon an arm of the said flier and movable thereon longitudinally and also in a radial plane, and the said flier-arm provided with a wing projecting alongside the

body-portion of the said presser-finger, and preceding the latter in the rotation of the flier to ward off blows from adjacent fliers.

6. In a flier, in combination, a flier-arm, a presser-finger movable upon the said flier-arm longitudinally and also in a radial plane, means for mounting the said presser-finger upon the flier-arm, and one or more prepared bearing-plates interposed between the proximate surfaces of presser-finger and flier-arm.

7. In a flier, in combination, the flier-arm having the screw-threaded holes tapped therein and counterbored around the said holes, the slotted presser-finger, one or more prepared bearing-plates interposed between

the proximate surfaces of presser-finger and flier-arm, the shouldered blocks or bushings within the slots of the presser-finger and having the reduced inner ends occupying the counterbores and the holes of the said bearing-plates, and the holding screws for the said presser-finger passing through the said blocks or bushings and occupying the said screw-threaded holes. 20

In testimony whereof I affix my signature 25 in presence of two witnesses.

FAY H. MARTIN.
